Patented Mar. 26, 1918.

UNITED STATES PATENT OFFICE.

ROBERT S. HEDGES, OF SAN ANTONIO, TEXAS, ASSIGNOR OF ONE-HALF TO JOSEPH P. ANDREWS, OF SAN ANTONIO, TEXAS.

VENTILATOR.

1,260,538.

Specification of Letters Patent.

Patented Mar. 26, 1918.

Application filed January 9, 1917. Serial No. 141,423.

To all whom it may concern:

Be it known that I, ROBERT S. HEDGES, a citizen of the United States, residing at San Antonio, in the county of Bexar and State 5 of Texas, have invented a new and useful Ventilator, of which the following is a specification.

The present invention appertains to ventilators, and aims to provide a novel and improved device of that character for use on 10 Pullman and passenger coaches, street cars, buildings and elsewhere.

It is the object of the invention to provide a ventilator of simple and inexpensive yet 15 practical and effective construction, and one having novel means for controlling the flow of air therethrough.

With the foregoing and other objects in view which will appear as the description 20 proceeds, the invention resides in the combination and arrangement of parts and in the details of construction hereinafter described and claimed, it being understood that changes in the precise embodiment of the invention herein disclosed can be made within 25 the scope of what is claimed without departing from the spirit of the invention.

The invention is illustrated in the accompanying drawing, wherein:—

30 Figure 1 is a horizontal section of the ventilator taken on the line 1—1 of Fig. 2.

Fig. 2 is a cross section taken on the line 2—2 of Fig. 1.

Fig. 3 is a sectional detail taken on the 35 line 3—3 of Fig. 2.

At the outset, it is pointed out that the present construction can be built in the railroad coach, street car, or other structure as a part thereof, and can be arranged in various positions according to its use.

The device embodies an elongated casing constructed of sheet metal, as illustrated, and comprising the back wall 1, top 2 (which may be the bottom if the device is in inverted position from that shown in Fig. 2), end walls 3 united with the back wall and wall 2, and longitudinal plate 4 united at its ends with the end walls 3 and bent on a longitudinal line to provide the bent back portion 5 outside of the casing. The plate 4 has its bend facing the back wall 1 and spaced therefrom to provide a longitudinal opening 6 across which a screen 7 is disposed, the respective edge of the back wall 1 being bent back or reflexed, as at 8, for the attachment

of the screen 7, and the bend of the plate 4 being formed, as at 9, for the attachment of said screen. The screen prevents the passage of cinders or other formed objects through the opening 6, and the casing can 60 be arranged in any suitable position for directing the air through the opening 6 in the direction desired.

The end walls 3 have the bent back U-shaped portions 10 and U-shaped members 65 11 are secured to the wall 2 and plate 4, to provide the openings 12 in the front of the casing. The openings 12 are in that side of the casing at right angles with the side having the opening 6.

The forward edges of the top 2 and plate 4 are bent back or reflexed, as at 13 and 14, to provide suitable bearings for rock shafts 15 which are journaled through said bent back or doubled portions centrally of the 75 openings 12. The forward edge of the bent back portion 5 is also reflexed or doubled, as at 16, to assist in supporting the shafts 15. Plates or dampers 17 are secured to the shafts 15 and are swingable therewith within the openings 12, said dampers closing the 80 openings when the dampers are brought into a longitudinal position.

As a means for operating the dampers, gear wheels 18 are secured to the shafts 15 85 between the plate 4 and its bent back portion 5, and mesh with a longitudinal rack bar 19 slidable within the guide formed by said plate and its bent back portion, the rack bar 19 bearing against the bend of the 90 plate and being slidable between said bend and the pinions 18. The rack bar 19 can be reciprocated by any suitable means, and from a distant point, for rotating the shafts 15.

A longitudinal series of transverse partitions 20 of sheet metal or other suitable material are secured to the back wall 1, plate 4 and wall 2, and terminate short of the front wall or side of the casing, said partitions 100 extending across the opening 6 and dividing the air into a plurality of streams. When the dampers 17 are swung in one direction as illustrated in full lines in Fig. 1, the inner side edges thereof move adjacent to certain of the partitions 20 for directing the air correspondingly, and when the dampers are swung in the opposite direction to the dotted line positions, as seen in Fig. 1, the other side edges of the dampers 110

are brought adjacent to the other partitions 20 for changing the flow of air correspondingly. The dampers 17 project from the openings 12 to catch the air and direct it into the casing and thence through the opening 6, or the dampers 17 can be so located that the air current passing the openings 12 will suck the air from the casing and opening 6, which ever action is desired.

10 Having thus described the invention, what is claimed as new is:

1. A ventilator embodying a casing having an air inlet opening in one wall and an outlet opening in another wall, partitions 15 within the casing transversely thereof extending across the outlet opening toward the inlet opening, and a damper mounted for oscillation within the inlet opening and swingable adjacent to different partitions 20 for directing the air thereto.

2. A ventilator embodying a casing having a longitudinal inlet opening in one wall and a longitudinal outlet opening in another wall, longitudinally spaced transverse 25 partitions within the casing extending across the outlet opening toward the inlet opening, a rock shaft journaled in the cas-

ing within the inlet opening, a damper carried by the rock shaft and swingable adjacent to different partitions for directing the 30 air thereto, and means for swinging said rock shaft.

3. A ventilator embodying a casing having an inlet opening in one wall and an outlet opening in another wall adjacent to said wall, the casing having a doubled portion between said openings, transverse partitions within the casing extending across the outlet opening, a rock shaft within the inlet opening and journaled in said doubled portion, 40 a damper carried by said shaft swingable adjacent to different partitions for directing the air thereto, a pinion secured to said shaft within the doubled portion, and a rack bar slidably in said doubled portion and 45 meshing with said pinion.

In testimony that I claim the foregoing as my own, I have hereto affixed my signature in the presence of two witnesses.

ROBERT S. HEDGES.
